UNITED STATES PATENT OFFICE.

JOHN E. REYNOLDS, OF DAYTON, OHIO, ASSIGNOR OF ONE-HALF TO PERRE E. GUSLER, OF SAME PLACE.

CASH-REGISTER.

SPECIFICATION forming part of Letters Patent No. 416,125, dated November 26, 1889.

Application filed July 11, 1889. Serial No. 317,206. (No model.)

To all whom it may concern:

Be it known that I, JOHN E. REYNOLDS, a citizen of the United States, residing at Dayton, in the county of Montgomery and State 5 of Ohio, have invented certain new and useful Improvements in Cash-Registers; and I do hereby declare that the following is a full, clear, and exact description of the invention, which will enable others skilled in the art to 10 to which it appertains to make and use the same, reference being had to the accompanying drawings, and to the letters and figures of reference marked thereon, which form a part of this specification.

15 My invention relates to improvements in cash-registers, the several features of which will be fully hereinafter described, and pointed out in the claims.

The objects of my invention are to indicate 20 on exposed dials by revolving hands the amount of a single purchase and to have said amount remain exposed until a subsequent purchase, when, automatically, by striking a bar, a bell is rung, and interior dials having 25 fixed pointers indicate the sum of any number of purchases, so that the amount of the latest purchase and the sum-total of purchases are always in view. I attain these objects by the mechanism illustrated in the accompanying drawings, (two sheets,) in which—

Figure 1 is a transverse horizontal section of the cash-register on line *x x*, Fig. 2. Fig. 3 is a front view of the machine with portions cut away. Fig. 4 is a transverse vertical section of the same on line *y y*, Fig. 2. Fig. 4 is 35 a transverse section of the clutch-coupling on line *t t*, Fig. 3.

Like letters and numbers designate like parts throughout the several views.

40 A is a wooden case having an opening or window at the top and a forward extension at the bottom, in which is held the drawer A'. This drawer is used to deposit the money and is held locked by the spring-catch 18, which 45 is attached to the side of the said drawer. The pulley 14 is attached to the back of the case, pulley 15 to the lower back corner, and pulley 16 is attached to the bottom near the front of the case. The cord 19 is attached to 50 the inner end of the drawer and is passed over the several pulleys, and to its upper end

is attached the weight 13. These parts are identical on both sides of the drawer and serve to carry the drawer partly out from the case when the catch is disengaged. The disengaging-rod 12 is held in supports 9 and 20, central in the case and near the front. A knob is attached to the top, and when it is struck by the hand it depresses the spring 18, thereby releasing the drawer. A pin is 60 put in the disengaging-rod beneath the top of the case, and this rests on the spiral spring 8 and arrests the upward movement of said rod by striking against the inner surface of said case. The lower end of said spiral spring 65 bears against the guiding-lug of the support 9. To a rear projection of this support is attached the bell 10, and at the lower end is pivoted the clapper 11. This is operated by a pin held in the disengaging-rod, and as this 70 is depressed the bell is rung. Lower down on the disengaging-rod are two pins, which give motion as the same is depressed to the pawls 4 and 5. (See Fig. 2.)

In bearings in the case are supported the 75 broken shafts L' L, which are connected by the coupling-clutch of parts E and O. The former is connected to the rear portion of said shaft and the latter to the forward portion. The part O enters the part E, and within the 80 former part is a recess in its face occupied by the clutch 21, which is backed by a spiral spring, and this clutch carries the rear portion of the shaft only to the left. The ratchet-wheels 6 and 7 are rigidly attached to the 85 two shafts, and to the pins s and r of the bar M are fastened the inner ends of the coiled springs 3, the outer ends being fastened to said ratchet-wheels. The bar M is supported on the post N, attached to the bottom of the 90 case. To the studs on the front wall of the case are pivoted the pawls 4 and 5, and these engage their respective wheels and prevent any movement of the shafts to the left while they are in engagement. These pawls may 95 depend for their movement on their gravity alone or may be backed by spiral springs. On the front of the case are attached the dials B B', concentric to the shafts, and these are numbered from 1 to 100, having a uniform 100 spacing about their peripheries. On the shafts outside of the dials are the hands C C',

and external to these are the knobs D D'. The knobs are for the purpose of turning said hands and the parts rigidly attached to the rear ends of the broken shafts. The ratchet-wheels have notches exactly corresponding to the divisions on the dials. The coiled springs 3 hold the hands C C' against their respective arresting-lugs u and v on the dials. To the rear portions of the broken shafts the two dials B² B³ are rigidly attached. These are identical with the front dials as to the divisions, but have the order of the numbering reversed, as shown at Fig. 2. C C³ are pointers attached to the top of the case and extend over the edges of said dials. On the shaft, to the rear of dial B², is attached the spur-wheel F, and this wheel engages the spur-wheel G, held on a hub attached to the rear central portion of the case. These wheels have each one hundred teeth. H is a wheel attached to the rear of the dial B³ on the shaft, and has only the one tooth 23, which engages the teeth on the contiguous wheel G. Directly over the left shaft is the bracket K, to which is pivoted the dial J, on the periphery of which are ten notches, the radial faces of which have numbers of from 100 to 1,000. This is rotated from left to right by the pin 22 on the rear of dial B².

The fixed dial B² indicates amounts in cents, the fixed dial B dollars, and the rotating dial J hundreds of dollars. The rotating dial or computation-wheel B³ indicates the sum-total of cents, and B² in dollars. The position of these wheels is indicated by the pointers C² C³. The former also indicates the position of the dial J or computation-wheel. In the normal positions the hands are at zero and the pointers likewise, and the operation is thus:

Turn the knob D until the hand points to 50 on the dial B'. The pawl 5 will engage a corresponding notch, and the hand will remain in a fixed position. Press down the disengaging-rod 12, and the ratchet-wheel 6 being released, through the recoil of the coiled spring 3, and the agency of the coupling-clutch the computation-wheel is carried to the left until the pointer C³ is directly over 50 of said wheel. The downward movement of rod 12 rings the bell and frees the money-drawer, so that it is carried out, that the money may be deposited. Move the hand again to 50 and release the pawl, as before, and the wheel H will have made one revolution, carrying the computation-wheel B² one mark to the left of the pointer C', indicating 100, or one dollar, when the pointer C³ will be again over zero. When the computation-wheel B³ has thus been partially rotated successively until a revolution is complete, the 100-mark of wheel J will be under the pointer C', thus indicating one hundred dollars, or ten thousand cents. If it were desired to record ten dollars, the hand C is turned to the right to 10. Then when the pawl 4 is released the amount would be indicated by the computation-wheel having its number 10 under the pointer C². Thus

the several sums are registered, and the total is seen by looking through the window W of the case and observing the numbers under the two pointers over the face of the three computation-wheels, and if care is taken the sum of money in the drawer would exactly correspond to that amount indicated on said wheels.

Having fully described my invention, what I claim, and desire to secure by Letters Patent, is—

1. The combination of case A, having cash-drawer A', with dial B', fixedly attached to the front of said case concentric to the shaft, shaft L, with hand C' attached, ratchet-wheel 7, with pawl 5 to engage said ratchet-wheel, coiled spring 3, the ends of which are united to said case and said ratchet-wheel, the coupling-clutch, which carries the rear portion of said shaft only to the left, the disengaging-rod 12, the computation-wheel B³, and pointer C³, whereby are registered all amounts less than one dollar, substantially as set forth.

2. The combination of case A, having suitable bearings for the shafts, the broken shafts L' L, the latter having hand C attached, dial B' on the front of said case, ratchet-wheel 7, with pawl 5 to engage said ratchet-wheel, coiled spring 3, the ends of which are united to said case and said ratchet-wheel, the coupling-clutch, computation-wheel B³, pointer C³, the one-cogged wheel H, cog-wheels G and F, and computation-wheel B², with pointer C², whereby are registered all amounts from one cent to one hundred dollars, substantially as set forth.

3. In a cash-register, the combination of the case A, having the numbered dial B attached to the front of said case, broken shaft L', to which is attached the hand C, ratchet-wheel 6, and pawl 4, to engage the same and to hold the hand to where it is placed on said dial, coiled spring 3, with ends attached to said case and to said ratchet-wheel, coupling-clutch, computation-wheel B², with pin 22, computation-wheel J, with numbers on its face and with pointer C² across its face, and the disengaging-rod 12, whereby are registered hundreds of dollars, substantially as set forth.

4. The combination of the coiled spring attached at its respective ends to the case and the ratchet-wheel, said ratchet-wheel, with its pawl pivoted to the case to hold the hand at a given point on the dial, the coupling-clutch, and the disengaging-rod to release said pawl, whereby through the resiliency of said spring and the grip of said clutch the amount is indicated by the hands C² C³ on their respective dials as hand C is stopped at pin v or zero.

5. The combination of the case A, having dials B B' rigidly attached to its front, the broken shafts L' L, with hands C C' to sweep over the faces of said dials, ratchet-wheels 6 and 7, with pawls 4 and 5 to engage their respective wheels and rigidly hold them until disengaged, the coiled springs 3, with their

ends united to said ratchet-wheels and to said case, the coupling-clutches of parts O, with catch 21 held therein, and part E, engaged by said catch when motion is given to the left 5 by the resiliency of said springs, computation-wheels B² B⁸, with numbers marked upon their faces, the wheel H, with the cog 23, cog-wheels G and F, pin 22 of said computation-wheel B², the computation-wheel J, moved

by said pin, the pointers C² C⁸, and the disengaging-rod 12, substantially as set forth.

In testimony that I claim the foregoing as my own I affix my signature in presence of two witnesses.

JOHN E. REYNOLDS.
